Patented Oct. 29, 1974

233,384

SUPPORT STRUCTURE FOR COCKTAIL BAR

Richard S. Stanuseich, June Stanuseich, and Michael Albert Thomas, all of 6933 Florin-Perkins Road, Sacramento, Calif. 95828

Filed Jan. 14, 1972, Ser. No. 218,045

Term of patent 14 years

Int. Cl. D6—06
U.S. Cl. D6—113

Fig. 1

Fig. 3

Fig. 2

FIG. 4

FIG. 5

FIG. 6

FIG. 1 is a rear perspective view of a support structure for cocktail bar, showing our new design;

FIG. 2 is a top plan view;

FIG. 3 is a side elevational view, the opposite side being a mirror image thereof;

FIG. 4 is a front elevational view;

FIG. 5 is a rear elevational view; and,

FIG. 6 is a bottom plan view.

We claim:

The ornamental design for a support structure for cocktail bar, as shown and described.
